UNITED STATES PATENT OFFICE.

RAYMOND WALTER McCLENON, OF FRANKLIN, NEW YORK.

DOOR-OPENING MECHANISM.

1,356,077.

Specification of Letters Patent. Patented Oct. 19, 1920.

Application filed December 15, 1919. Serial No. 345,115.

To all whom it may concern:

Be it known that I, RAYMOND W. McCLENON, a citizen of the United States, residing at Franklin, New York, have invented 5 new and useful Improvements in Door-Opening Mechanism, of which the following is a specification.

The present invention relates to improvements in door opening mechanism, more 10 particularly to an arrangement whereby a door or other movable structure may be swung open, its support or carrying member retained in an opened position and which also includes means to return the same to its 15 normal position at such time as desired.

A further object of the invention is to provide an improved arrangement of the character set forth above which may be manipulated by the foot of the operator at 20 a point either inside or outside.

Various other objects and advantages of my invention will become apparent during the continuance of the following description.

25 In the drawings:—

Figure 1 is a view in front elevation with the door sill shown in sections.

Fig. 2 is a view in cross-section of a door showing the operating means therefor in 30 top plans.

Fig. 3 is a fragmentary view of the door sill showing means to retain the door in an opened position.

Fig. 4 is a view in perspective of a bolt.

35 In the drawings 10 designates a suitable supporting structure hereinafter referred to as the door sill and 11 indicates the door jamb. The sill 10 is cut away as shown at 12 and is provided in such cut-away portions with supporting sockets 13 that receive the lower end of the door carrying rods 14 and 15 respectively. The rods 14 and 15 extend upwardly to the sides of the jamb 11 and pass through bushings 16 of the sill 10 45 and carrying sleeves 17 of the jamb. The door members 18 carry sleeves or bearings 19 which embrace the rods 14 and 15 as shown in Fig. 1 so as to provide for the proper supporting thereof. From this arrangement, it will be readily seen that the doors 18 are free to swing upon the rods 14 and 15 from an open to a closed position and vice versa.

50 A small carrying arm 20 is arranged below the sill 10 and has connected therewith oppositely extending chain members 21 and

22 which in turn have their outer ends wound about and secured to the lower portion of the rods 14 and 15.

Operation members, such as shown in 60 Fig. 4 are now provided which consist of a bolt 23 which extends upwardly through openings 24 in the sill and which are adapted to be engaged by the foot of the operator, a base 25 adapted to ride upon the chain 65 members 21 and 22 and arms or fingers 26 which extend on each side of the chain members as shown in Fig. 1. It will now be observed that by applying pressure to the upper or free end of the extension 23, the 70 base 25 of the operating member will be depressed, thus forcing the chain members backwardly so as to cause the same to unwind from the respective rods 14 and 15. Such action of the chain member will cause 75 the doors to move into an opened position.

In order to provide means to retain the doors or other movable members in an opened position, I provide leaf springs 27 which may be secured to the floor or sill 80 10 as at 28 and which have their free ends which normally project above the level of the sill bent at substantially right angles to form a shoulder 29 and a depending lug 30. The lug 30 projects through an opening 31 in the sill, as shown in Fig. 3 so that when pressure is applied thereto, the spring 27 may be drawn backwardly to a position substantially level with the sill. When in the latter position, the spring will 90 allow the doors to move freely thereover.

A stud 32 is slidably mounted on sill 10 and through a bushing 33 is connected at its lower end with one end of a chain or other small connecting member 34. The 95 chain 34 works over a pulley or other bearing surface 35 and is connected at its other end to the lower end of the lug 30 of the spring 27 as at 36. From this construction, it will be seen that when pressure is 100 applied to the stud 32, the chain 34 will be drawn from the pulley 35 thus causing the spring 27 to become depressed.

It is also desirable to provide suitable means to retain the doors in a normally 105 slow position to yieldingly resist the opening thereof. To this end, I provide coil springs 37 which are arranged about the rods 14 and 15, one end of each spring bearing against the door jamb and the 110 other end of each spring bearing against the respective door member.

In operating, assuming that the doors are in a closed position, as shown at Fig. 1, the pressure upon either of the members 23 will cause the depression of the chain members 21 and 22 which will in turn cause the unwinding of the chain members from the rods 14 and 15, thus rotating the rods so as to move the door members into a position shown in dotted lines in Fig. 2. To close 10 the doors, the operator simply depresses the stud 32 which through the medium of the chain 34 moves the leaf springs 27 to release the doors and the latter will move into a closed position by action of the coil 15 spring 37.

From the foregoing, it is believed that the advantages and novel features of my invention will be readily understood and therefore further detailed description is 20 deemed unnecessary.

Having thus fully described my inven-

tion what I claim as new and desire to secure by Letters Patent is:

In a device of the character described, the combination with a supporting structure including a door sill, of carrying standards movably mounted thereon, doors carried by said standards and movable therewith, operating cables, the ends of said operating cables being wound about said 25 carrying standards, actuating studs movably mounted in said supporting structure, bifurcated heads on said studs overlying said cables and said studs being adapted to actuate said cables to move said carrying 30 standards and said door members substantially as described.

RAYMOND WALTER McCLENON.
